UNITED STATES PATENT OFFICE.

AMOS F. DIXON, OF NEWARK, NEW JERSEY, ASSIGNOR, BY MESNE ASSIGNMENTS, TO
WESTERN ELECTRIC COMPANY, INCORPORATED, A CORPORATION OF NEW YORK.

PRINTING-TELEGRAPH RECEIVER.

1,194,365.

Specification of Letters Patent. Patented Aug. 15, 1916.

Application filed March 20, 1914, Serial No. 825,996. Renewed February 16, 1915. Serial No. 8,619.

To all whom it may concern:

Be it known that I, AMOS F. DIXON, a citizen of the United States, residing at Newark, in the county of Essex and State of New Jersey, have invented a certain new and useful Improvement in Printing-Telegraph Receivers, of which the following is a full, clear, concise, and exact description.

This invention relates to printing telegraph receivers and more particularly to receivers wherein the characters may be simultaneously produced in two different forms.

One of the objects of this invention is to produce an improved receiver of the above type which is simple in construction and reliable and efficient in operation.

A further object is to produce an improved controlling system whereby one of the reproducing mechanisms may be rendered operative and inoperative at will.

To the above ends, in combination with improved type and punch selecting mechanism, there are provided circuit preparing and completing devices whereby the actuation of the punching mechanism may be controlled.

The above and other objects of this invention will be fully set forth in the following description and claims, and will be more readily understood by reference to the accompanying drawings in which—

Figure 1 is a perspective showing the preferred embodiment of the invention arranged for simultaneously printing characters and perforating a paper tape; Fig. 2 is a plan of a modification of the tape perforating portion of the apparatus; Fig. 3 is a cross-section taken on the line 3—3 of Fig. 2; Fig. 4 is a cross-section taken on the line 4—4 of Fig. 3; Fig. 5 is a cross-section taken on the line 5—5 of Fig. 3; Fig. 6 is a diagram of the system of circuit connections for causing and controlling the operation of the preferred embodiment of the invention, and Fig. 7 is a similar circuit diagram adapted to the modified form of the invention.

Similar letters of reference refer to similar parts throughout the several views.

The tape perforating mechanism or punch block is similarly constructed in both the preferred embodiment and the modification, and consists of the following parts: A frame or housing 11 having uprights 12—12 on

which rest a punch guide member 13, which 55 is provided with a plurality of openings through which a number of character punches 14 and a similar feed hole punch 15 are adapted to reciprocate. Each punch has projecting therethrough a spring member 16 60 secured at one end to the guide member 13 and normally resting at the other end on an angle stop-piece 17. These springs are for the purpose of returning the punches to normal position after the punching operation has been performed. Mounted upon the base of the frame 11 is an electromagnet 18 having an armature 19 pivoted upon a shaft 20, which is held in pedestal bearings 21, 22. The uprights 12, 12 furnish bearings 70 for a shaft 23 and the shafts 20 and 23 are joined by a suitable coupling 24. Beneath the punches 14 and 15 is a punch operating member which consists of a hardened head 25 carried by a lever 26, which is securely 75 mounted on the shaft 23 to rotate therewith when the electromagnet 18 attracts its armature 19. A suitable spring (not shown) may be provided to return the armature to normal position after the deenergization of 80 the electromagnet 18.

Each of the character punches 14 has an associated lever 28, the free end of which may be projected between the corresponding punch and the striking head 25 so that when 85 the electromagnet 18 is energized, the corresponding punches will be driven through a paper tape 29. The feed punch 15 is of sufficient length and so located as to be struck and driven through the tape upon 90 every advance of the striking head 25. The levers 28 are pivoted at 30 to a second set of levers 31 which are pivoted between the extensions 32, 32 integral with the uprights 12, 12. The opposite ends of levers 31 are 95 joined at points 10 in the preferred arrangement, shown in Fig. 1, to links 33, and in the modification, shown in Figs. 2, 3, 4 and 5, to links 34.

The shaft 23 carries, besides the lever 26, 100 an arm 35 upon which is pivotally mounted a feed pawl 36. This pawl is adapted to engage the pins in the circumference of a tape advancing wheel 37 which is mounted upon a shaft 38 supported in bearings in the 105 guide member 13. A spring 39 secured to arm 35 and to pawl 36 causes the pawl to engage the pins in the feed wheel 37 to ad-

vance the wheel when the shaft 23 is rotated in a clockwise direction, but allows the pawl 36 to slip over the pins when the shaft 23 is rotated in an anti-clockwise direction. 5 During the return movement of the pawl 36, feed wheel 37 is prevented from being rotated in the reverse direction by means of a spring-pressed pawl 41 resting between the teeth of a ratchet wheel 42 likewise mounted 10 on the shaft 38. Pins of the feed wheel 37 engage with the holes in the tape 29, which are punched by the feed punch 15 at every energization of electromagnet 18, and upon the deenergization of electromagnet 18 advance the tape to present an unpunched area 15 for a succeeding punching operation.

Referring now to the modified form of the invention, as shown in Figs. 2, 3, 4 and 5, the mechanism for selecting combinations of 20 levers 28 to be interposed between the corresponding punches 14 and striking head 25, for perforating corresponding holes in the tape, consists of five electromagnets 45. These magnets 45 are provided with armatures 47, the free ends of which are joined each one to a link 34. The energization of any one or a combination of magnets 45, as hereinafter described, will attract the corresponding armatures 47 and consequently 25 cause the projection of corresponding levers 28 between corresponding punches 14 and the striking head 25 for perforating the tape.

Referring now more particularly to the 30 right-hand portion of Fig. 1, the production of a similar selection of levers 28 is accomplished by having the links 33 attached directly to selecting disks 48, 49, 50, 51 and 52. These disks constitute part of an apparatus capable of printing the message in page form, only enough of which has been shown to give a complete understanding of the operation of selecting the desired characters. The five electromagnets 54 to 58 inclusive are conveniently placed around the selecting disks 48 to 52 inclusive and have their armatures 59 connected each one, by means of a link 60, to a corresponding disk. Electromagnets 54 to 58 are adapted, when 45 energized, as hereinafter described, to attract their respective armatures 59 and thereby cause a slight rotation of the corresponding selecting disks 48 to 52. It is evident then that, by the energization of various combinations of these electromagnets, corresponding levers 28 are selected and interposed between punches 14 and head 25 to produce corresponding combinations of holes in the tape 29. These electromagnets also 50 serve to select the characters to be printed in page form from type wheel 53 carried by a rotatable shaft 61. Type wheel 53 has two rows of raised type characters arranged upon its surface. The shaft 61 is adapted to 55 be kept constantly under proper tension by

means of any suitable motor mechanism (not shown), which causes it to tend to rotate in the direction of the arrow of Fig. 1. Normally, however, shaft 61 is prevented from so rotating by a stop 66 engaging the teeth 70 of a ratchet 67. The selecting disks 48 to 52 are each provided with a series of notches 62, two of such series only being shown in the drawing, but there should be one notch in each disk corresponding to each vertical line of characters carried by the type wheel, and in addition, one corresponding to each of the other selecting operations to be performed by the apparatus, such, as cutting in and out of the perforating mechanism, 75 spacing, feeding, etc. Before each of the vertical lines of notches 62, corresponding to a character to be printed, is positioned a pivoted spring-tensioned type selecting lever 63 which is adapted, under certain conditions to be hereinafter described, to engage with a contact arm 64 carried by shaft 61. Before the vertical lines of notches 62 representing other operations than the selection of characters are also positioned spring-tensioned levers which are adapted to control circuits whereby the proper electromagnetic devices for performing such desired functions are energized. Two of these levers are referred to in Figs. 6 and 7 by the reference 80 characters 127 and 146. The notches 62 are so located that, a combination of selecting disks being slightly rotated by the energization of the corresponding electromagnets, there will be presented a continuous vertical 85 line thereof before only one of the type or operation selecting levers 63. The springs 65 of all the type selecting levers tend to raise the centrally projecting ends thereof into a position to engage the rotating arm 90 64, whereby the type wheel 53 may be stopped. The selecting levers 63 are, however, normally held out of engagement with the selecting disks until the completion of a cycle of selecting operations by release lever 95 68 pivoted at 69. The centrally projecting circular-shaped ends 70 of the lever 68 engage and hold the selecting levers 63 depressed under the tension of a spring 71. A release magnet 72 acting on the armature 73 100 forming part of lever 68, however, when energized, elevates the ends 70 away from the centrally projecting portions of the selecting levers 63. The particular one of said levers 63 having a complete vertical line in front 105 of its vertical shank will therefore move sufficiently to initiate the performance of the desired functions. The character is thereby presented to the printing plate, which may be any well known electromagnetic device 110 having a hammer adapted to press the paper against the type wheel. If any of the operation selecting levers 63 had been operated, it would not have caused the selection of a 115 character, but the closing of contacts to set 120

in motion the proper electromagnetic devices for spacing or feeding the paper, or accomplishing any other desirable operation.

The apparatus and system may be understood by the following detailed description of the operations necessary for receiving and reproducing a character in printed and perforated form. Fig. 6 shows a circuit which may be used with the preferred embodiment of the invention as shown in Fig. 1, and by referring to these two figures it will be shown how the selection of a particular character and the cutting in and out of the perforating mechanism are controlled from the sending end of a main line L.

The sending apparatus at a distant station may be assumed to send various combinations of five positive and negative impulses. These impulses arrive over a main line conductor L and pass to ground through the windings of a polarized relay 74 which is energized by positive current to connect battery 75 to conductor 76. Conductor 76 is connected to a conducting ring 77 of a current distributor 78, which is divided in four equal parts, only one of which is shown connected up to a receiving instrument for the sake of clearness. The distributor 78 is provided with a rotatable arm 79 which is driven in the direction of the arrow by any suitable source of power. The arm 79 is provided with a pair of insulated contact brushes which are adapted to successively unite a series of commutator segments 80, 81, 82, 83 and 84 and the conducting ring 77. Therefore, when the received impulses are positive, battery 75 is connected to the corresponding conductors 85, 86, 87, 88 and 89 and lastly, battery 90 is connected through segments 91, 92 to conductor 93. The conductors 85, 86, 87, 88 and 89 are connected, respectively, to intermediate relays 94, 95, 96, 97 and 98, each one of which is provided with an armature permanently connected to one of the selecting magnets 54, 55, 56, 57 and 58 by conductors 100, 101, 102, 103, and 104 respectively.

Let it be assumed that a character is to be selected by five impulses combined in the following order: positive, negative, negative, positive, negative. Upon the reception of the first positive impulse, the brushes on arm 79 of the distributor 78 connect the conducting ring 77 with the segment 80 and a circuit is thereby established from grounded battery 75, conductor 76, ring 77, segment 80, conductor 85, relay 94, conductor 107, a release control relay 108, conductor 109, back contact and armature of clear-out relay 110 to ground. Relay 94 thereupon attracts its armature 105, establishing an energizing circuit for magnet 54 and a holding circuit for itself as follows: grounded battery 111, selecting magnet 54, conductor 100, armature 105, front contact 106, conductor

107, release control relay 108, conductor 109, and to ground at the armature of clear-out relay 110. Release control relay 108 also attracts its armature and is held by the holding circuit above traced, but performs no function at this stage of the operation. The energization of selecting magnet 54 causes the attraction and the holding of its armature 59 and a corresponding movement of disk 48 through the lever 60 takes place. The second and third impulses arrive over the main line L, while the brushes on arm 79 pass over segments 81 and 82, respectively, but being of negative sign cause the armature of polarized relay 74 to rest against its inactive contact, and battery 75 is therefore not connected with relays 95 and 96; consequently, selecting magnets 55 and 56 and their corresponding disks 49 and 50 remain inactive. The fourth impulse being of positive sign causes a reversed action of the polarized relay 74 which connects battery 75 to conductor 76, while the brushes on arm 79 connect ring 77 with segment 83. A circuit is therefore completed from grounded battery 75, conductor 76, ring 77, segment 83, conductor 88, relay 97, conductor 107, release control relay 108, conductor 109, back contact and armature of clear-out relay 110 to ground. Relay 97 attracts its armature and closes an operating and holding circuit from grounded battery 112, selecting magnet 57, conductor 103, armature, front contact and coil of relay 97, conductor 107, release control relay 108, conductor 109, and to ground at back contact and armature of clear-out relay 110. The closing of this circuit causes the selecting magnet 57 to move its corresponding disk 51. The fifth impulse arrives over the main line L while the brushes on arm 79 pass over segment 84, but being of negative sign, no current will flow to energize electromagnet 58. The selecting relays 94 and 97, the release control relay 108 and selecting magnets 54 and 57, remain energized and the movement of their respective disks 48 and 51 causes the presentation of a continuous vertical line of notches 62 before the selecting lever 63 corresponding to the positioning of a certain character upon the type wheel 53 before the printing platen. After the brushes of arm 79 have passed by the segment 84, it passes over and unites segments 91 and 92, thereby causing a circuit to be established from grounded battery 90, segments 91, 92, conductor 93, front contact and armature of release control relay 108, conductor 114, release relay 116, conductors 117 and 109, back contact and armature of clear-out relay 110 to ground. Release relay 116 attracts its armature, closing an operating and holding circuit for the release magnet 72 as follows: grounded battery 120, release magnet 72, conductor

118, through the release relay 116 by way of its front armature and contact, conductors 117 and 109 to ground at armature of clear-out relay 110. The energization of release magnet 72 causes the movement of release lever 68 against the tension of spring 71, which removes the ends 70 from engagement with the inner ends of all selecting levers 63, whereupon the selecting lever 63, before 10 which a continuous vertical line of notches 62 is presented, raises its centrally projecting end into a position to engage the arm 64 carried by shaft 61. The shaft 61 is then released by the removal of the pawl 66 from 15 ratchet wheel 67 by means of any suitable electromagnetic device and circuit arrangement. The shaft 61 thereupon rotates in the direction of the arrow until the arm 64 strikes the elevated end of the selecting lever 63 at which time the assumed character is presented in front of the platen in position to be printed. The energization of release relay 116, closes through its front contact a circuit connection for the perforating magnet 18, which may or may not be effected; 20 depending upon whether or not it is desirable to have the message reproduced in punched tape form. Assuming at present that such a performance is not desirable, 25 only the printing of the selected character will take place as follows: Upon the engagement of lever 63 and arm 64, a circuit is closed from grounded battery 122, clear-out relay 110, conductors 123 and 124, the printing magnet 125, arm 64, lever 63 to ground at 126. The printing magnet is then energized and the printing is effected. Clear-out relay 110 is also energized and removes the ground from conductor 109, whereupon 30 the apparatus is released to normal in the following manner: The ground connection being removed, as stated, from the release control relay 108, the release relay 116, relays 94 and 97, the selecting magnets 54 and 45 35 and 57 and the release magnet 72 are allowed to return to normal. The return of the release lever 68 depresses the elevated end of the connecting lever 63 and breaks the contact between lever 63 and the arm 64, thus 40 removing the ground connection for the printing magnet 125 which, together with the clear-out relay 110, returns to normal.

Assuming now that it is desirable to connect the perforating mechanism to the apparatus for the simultaneous recording of the message in both printed and perforated form, a series of impulses is first sent over main line L to effect the selection and operation of the selecting lever 127, which prepares the apparatus for the operation of the perforating mechanism. These impulses have the same effect as those for selecting a type selecting lever 63, with the difference that the printing magnet 125 is not energized and the type shaft 61 is not released.

The lever 127 having been thus selected, establishes a circuit connection for relay 130 as follows: from grounded battery 122, clear-out relay 110, conductors 123, 131, contact 132, lever 127, left-hand coil of relay 130 to ground. Relay 130 is then energized and provides a locking circuit for itself from grounded battery 133, armature and back contact of a relay 134, conductor 135, right-hand front contact, armature and coil of relay 130 to ground. All parts are then released to normal due to the energization of the clear-out relay 110, the same as in the selection of a character. It will be noted, however, that the relay 130 remains locked up and the perforating mechanism is now permanently cut in so that any subsequent selection will be produced thereon in the form of a punched tape. This perforation of tape is accomplished through the medium of the selecting disks. These disks are, as previously stated, selected in various combinations and caused to interpose corresponding levers 28 between corresponding punches 14 and the striking head 25, through the medium of levers 33 and 31. These selected punches will then be driven through the tape when the magnet 18 is energized. This magnet 18 is energized every time a selection of a character is performed through a circuit established from grounded battery 137, magnet 18, front contact and armature 138 of release relay 116, conductor 139, armature 140 and front contact of relay 130 to ground.

Should it be desired to disconnect the perforating mechanism, a combination of impulses is sent from the distant station over main line conductor L to operate the selecting lever 146. The selection of this lever 146 causes the contact 147 to be closed to ground and a circuit established from grounded battery 122, clear-out relay 110, conductors 123, 131 and 148, relay 134, contact 147 and lever 146 to ground. This circuit energizes relay 134 and breaks the locking circuit through its back contact and armature of relay 130, which is then de-energized and removes the ground from conductor 139, which as stated above determines whether or not the magnet 18 will be energized.

The system of connections shown in Fig. 7 is adapted to be used in connection with the modified perforating mechanism shown in Figs. 2, 3, 4 and 5. Its operation is substantially the same as that of the system of Fig. 6, except for the selections of the perforating mechanism which are made through the medium of the magnets 45, previously described and shown in Fig. 7 connected in series with the selecting magnets 54, 55, 56, 57 and 58. It is evident then that each of the magnets 45 is selected in unison with the corresponding magnet 54, 55, 56, 57 or 130.

58 and is caused to project a corresponding lever 28 between the corresponding punches 14 and the striking head 25. The magnet 18 is operated in the same manner as in the 5 system shown in Fig. 6.

What is claimed is:

1. A receiving apparatus comprising two sets of selecting members, apparatus for controlling said sets of members simultaneously, an operative instrumentality adapted to coöperate with one of said sets, means affected by the other said set for partially controlling the coöperation of said instrumentality and its associated set, and an electro-responsive device controlled by said apparatus independently of said sets for likewise partially controlling the coöperation of said instrumentality and its associated set.
2. In a telegraph receiver the combination of a plurality of selecting members, means for selecting combinations of said members, a plurality of perforating punches, a plurality of punch selecting mechanisms controlled by said members, an operating means for said punches, a controlling circuit for said operating means, contacts controlled by said members, means controlled by said contacts to partly prepare said circuit, and electromagnetic means operated by the selecting means for completing said circuit.
3. In a telegraph receiver, the combination of a plurality of selecting members, a perforating reproducer adapted to be prepared for operation by said members, an operating means for said reproducer, a controlling circuit for said operating means, contacts therefor controlled by said members, to partly prepare said circuit, and an electroresponsive device for completing said circuit independently of said members.
4. In a telegraph receiver, the combination of a plurality of selecting disks, a perforating reproducer adapted to be prepared for operation with said disks, an operating means for said reproducer, a controlling circuit for said operating means, two sets of contacts controlled by said disks, means controlled by one set of said contacts to partly

prepare said circuit, independent means for completing said circuit, and means controlled by the other set of said contacts to open said circuit.

5. In a telegraph receiver, the combination of a plurality of selecting disks, a perforating reproducer adapted to be prepared for operation by said disks, an operating means for said reproducer, a controlling circuit for said operating means, two sets of contacts controlled by said disks, a relay 55 operated by one set of said contacts to partly prepare said circuit, means for completing said circuit, a locking circuit for said relay operated by the same set of contacts, and a second relay controlled by the other set of 60 said contacts to open the locking circuit for the first mentioned relay.

6. In a telegraph receiver, the combination of a plurality of selecting disks, means for selecting combinations of said disks, a 70 perforating reproducer, means operated by said selecting means to prepare said reproducer for operation, an operating means for said reproducer, a controlling circuit for said operating means, contacts controlled by 75 said disks, means controlled by said contacts to partly prepare said circuit, and means for completing said circuit.

7. In a telegraph receiver, the combination of a plurality of selecting disks, means 80 for selecting combinations of said disks, a perforating reproducer, a printing reproducer, means operated by said selecting means for operating said printing reproducer, means operated by said selecting 85 means to prepare said perforating reproducer for operation, operating means for said reproducer, a controlling circuit for said operating means, contacts controlled by said disks, means controlled by said contacts to partly prepare said circuit, and means for completing said circuit.

In witness whereof, I hereunto subscribe my name this 17th day of March A. D., 1914.

AMOS F. DIXON.
